UNITED STATES PATENT OFFICE.

POVL T. LINDHARD, OF BROOKLYN, NEW YORK, ASSIGNOR TO F. L. SMITH & CO., OF NEW YORK, N. Y., A CORPORATION OF NEW JERSEY.

LINER FOR TUBE MILLS.

Application filed October 1, 1926. Serial No. 138,848.

In another application of the present applicant for Letters Patent of the United States, Serial No. 42,868, filed July 11, 1925, there is described an improvement in liners for tube mills, etc., in accordance with which the liner is made up of longitudinal bars of metal with rounded working faces, intervening spaces, bridge pieces connecting the bars at intervals and a filling of cement 5 grout between the bars, the purpose being to secure greater efficiency and endurance in operation as compared with the cast metal liners sometimes employed and of greatly reduced cost, as compared with the six 10 liners. Long continued use of liners constructed as described in that application has shown that they have great efficiency for a long period of use, giving a production capacity of seventy-five barrels of cement 15 per hour, as compared with a production capacity of about forty-five barrels per hour of mills lined with the best cast metal liners, but have not the endurance desired, the working surface, properly corrugated at the 20 outset, becoming smooth, so that the efficiency falls off greatly, while yet there remains a substantial thickness of the liner which must be taken out and replaced by a new liner. It will be understood that continued efficiency of a mill equipped with the liner, under normal conditions of operation, depends upon the maintenance of a corrugated surface which, in the rotation of the mill, will cause the grinding bodies to be 25 raised to the proper height so that grinding action shall be maintained as they tumble down the ascending side of the mill, and that, for continued efficiency, the corrugated working surface should be maintained until the liner is worn so thin that its replacement involves a minimum of waste. In the development of the liner described in that application it was thought to be desirable to fill the spaces between the metal bars 40 with a relatively softer material, such as cement grout, in order that such filling might wear away in proportion to the wearing away of the metal bars, and the corrugation of the working surface be thereby maintained. It was thought to be desirable to give to the spaces intervening between the bars a width as great as or somewhat greater than the minimum dimension of the grinding bodies, such as the short cylindrical 45 bodies known as cylpebs, and as little as or somewhat less than the maximum dimension of such bodies. A liner so constructed was found to give satisfactory results for a time, but became so smooth that the capacity of the mill fell off materially before the liner 50 was worn out. Continued investigation has shown that when the spaces between the bars, in the direction of rotation of the mill, are as narrow and are shaped as shown in the drawings of that application, the grinding bodies themselves pack into such spaces, when the cement filling is worn out, and remain there, thus causing the liner to lose its corrugated working surface and to present a comparatively smooth working surface, such that the capacity of the mill falls off considerably. Such continued investigation has also resulted in the development of the present invention, in accordance with which it has been determined that the continued efficiency of the liner is dependent upon the angle between the lateral faces of adjacent bars and preferably upon the relation between that angle and the coefficient of friction between the grinding bodies and the lateral faces of the bars, the angle and the relation between the angle and the coefficient of friction being such that there shall be no tendency of the grinding bodies to pack and remain in the spaces between the bars. It has been found that the best results are secured when the angle between the adjacent working faces of the bars is approximately but not less than thirty degrees and such that the tangent of one-half of the angle shall be substantially equal to or larger than the coefficient of friction between the grinding bodies and the bars. The use of cement grout as a backing to secure the metal liner blocks in place is desirable but its use as a filling between the bars is unnecessary. Incidentally, also, a means has been devised for strengthening the liner blocks in the bridge pieces at the ends of the longitudinal spaces between the bars, with a subsequent reduction of liability to cracking at such points.

The invention will be explained more fully hereinafter with reference to the accompanying drawings, in which:

Figure 1 is a face view of a liner block, comprising a plurality of spaced bars cast in one block and embodying the invention.

Figure 2 is a view of the same in longitudinal section on the irregular plane indicated by the broken line 2-2 of Figure 1.

Figure 3 is a transverse section on the plane indicated by the broken line 3-3 of Figure 1.

Figure 4 is a transverse section showing several blocks or bars applied to the shell of the mill with a backing of cement grout to hold the blocks in place.

Figure 5 is a face view showing the placing of the blocks in a mill so as to break joints.

Figure 6 is a view in transverse section, on a larger scale than that of Figure 4, illustrating the manner of coaction of cylindrical grinding bodies with the improved liner.

Longitudinal bars α , α , of a length convenient for handling and preferably having a rounded working surface α^1 and a recessed rear surface α^2 , are united by casting in a block for convenience in handling and in application to the shell of the mill, with a suitable curvature of the block, the bars being separated from each other by longitudinal spaces, which preferably penetrate the block from face to back and are transverse to the direction of movement of the grinding bodies. The bars are preferably united at intervals by bridge pieces c which, as shown in Figure 2, preferably do not extend to the working face of the block; but leave, in the front portion of the block, channels which extend continuously from end to end. Each outer bar of the block is preferably formed at its outer side with spacing projections h so as to provide spaces between the adjacent bars of adjacent blocks.

In order that the bars or the blocks of bars may be conveniently secured in the shell of the mill, cement grout f is used as a backing, filling the channels at the rear face or back of the block and perhaps entering to some extent into the spaces b between the lateral faces of the bars and thereby further assisting in securing the metal liner in place.

In order that the blocks may be strengthened at their ends and the possibility of cracking through the bridge pieces c at the ends may be reduced, tinned bars of iron i , transverse to the longitudinal axis, are set into the mold in which the blocks are cast and the blocks are cast upon them.

The spaces b between the lateral faces of the bars are given such width as to receive freely the grinding bodies g and are so formed that there will be no tendency of the grinding bodies to pack and lodge therein during the operation of the mill. It has been found desirable that the angle between the lateral faces of the bars should be no

less than about thirty degrees and that in any case it should be substantially equal to or larger than the coefficient of friction between the grinding bodies and the material of which the bars are formed. When this angular relation is observed, it will be found that the corrugation of the working surface of the liner will be maintained until the bars are worn to such a thinness that they become liable to breakage and to require replacement.

I claim as my invention:

1. A liner for tube mills, etc., having longitudinal bars of metal spaced apart transversely to the direction of movement of the grinding bodies and having the lateral faces of adjacent bars formed in planes at an angle to each other so that the tangent of one-half of such angle shall not be substantially less than the coefficient of friction between the grinding bodies and the material of which the bars are formed, whereby the packing and lodging of the grinding bodies in the spaces between the bars is prevented and the corrugation of the working surface of the liner is maintained.

2. A liner for tube mills, etc., having longitudinal bars of metal spaced apart transversely to the direction of movement of the grinding bodies and having the lateral faces of adjacent bars formed in planes at an angle to each other of not substantially less than thirty degrees, whereby the packing and lodging of the grinding bodies in the spaces between the bars is prevented and the corrugation of the working surface of the liner is maintained.

3. A liner for tube mills, etc. comprising blocks of longitudinal bars of metal with intervening spaces and connecting bridge pieces, the bars having the lateral faces of adjacent bars formed in planes at an angle to each other so that the tangent of one-half of such angle shall not be substantially less than the coefficient of friction between the grinding bodies and the material of which the bars are formed, whereby the packing and lodging of the grinding bodies in the spaces between the bars is prevented and the corrugation of the working surface of the liner is maintained.

4. A liner for tube mills, etc. comprising blocks of longitudinal bars of cast metal with intervening spaces and connecting bridge pieces and transverse rods of metal upon which the block is cast through the bridge pieces at the ends of the bars to strengthen the blocks and reduce the liability to cracking.

This specification signed this 30th day of Sept., A. D. 1926.

POVL T. LINDHARD,
